UNITED STATES PATENT OFFICE.

CHARLES E. JEWETT, OF NORTH ANDOVER, AND FRED FITZGERALD, OF LAWRENCE,
MASSACHUSETTS.

STOP-MOTION FOR COMBS.

1,299,187.

Specification of Letters Patent.

Patented Apr. 1, 1919.

Application filed September 20, 1918. Serial No. 254,921.

To all whom it may concern:

Be it known that we, CHARLES E. JEWETT, a citizen of the United States, residing at North Andover, in the county of Essex and State of Massachusetts, and FRED FITZGERALD, a citizen of the United States, residing at Lawrence, in the county of Essex and State of Massachusetts, have invented certain new and useful Improvements in Stop-
10 Motions for Combs, of which the following is a specification.

This invention relates to stop motions for worsted combs, particularly of the circular type.

15 Its purpose is to provide mechanism which will stop the comb when a ribbon of sliver breaks between the sliver delivery means, such as the drawing-off rolls and drawing-off aprons, and the trumpet through which it passes on the way into the can coiler or other receiving device.

20 The advantages of our device are that it is simple and can be easily attached, while it is sensitive and has a quick positive action and, after it has operated to stop the comb, it resets itself automatically with no special attention from the operator.

Besides this, the faller or feeler wires for the sliver, between the sliver delivery means and the trumpet, are of such character that each can readily be associated with and operated by a suitable arm connected with a drawing-off roll or an apron roll bearing. When so connected, such faller wire will be 30 so moved as to operate the comb stopping mechanism when the roll or bearing to which it is connected goes backward as, for instance, when an apron breaks and winds up on its roll.

40 Our device can be most readily attached to a comb in which the whole trumpet revolves, but where a stationary trumpet is used, we can leave the mouth of the trumpet stationary and make another part of it revolute.

45 Figure 1 is a diagrammatic plan view of a circular comb, showing the large and small circles, the drawing-off aprons, trumpet, shipper, and other parts necessary to understand our invention, but omitting other well-known parts common to such combs. Fig. 2 is an elevation, in perspective, showing the parts of the comb necessary to understand our invention. Fig. 3 is an enlarged eleva-

tion, in perspective, showing the trumpet 55 and its attachments together with the actuator operative therefrom. Fig. 4 is an enlarged elevation from the side of a trumpet with its attachments, the casing being shown partly in section. Fig. 5 is a vertical, and 60 Fig. 6 a horizontal section of the actuator and trigger mechanism. Fig. 7 is a detail thereof. Fig. 8 is a diagrammatic side elevation showing a modification of our construction with plate 78 raised, and Fig. 9 is 65 a view from the right of Fig. 8, the trumpet being shown in section on line 8—8, and plate 78 being shown as down. Fig. 10 is an elevation showing the end of the arm from the apron roll bearings. Fig. 11 is a 70 plan view in detail of a modification of the end of such arm.

A represents the large circle of a circular comb, and B and C represent the small circles thereof. D and E represent the whole 75 of each sliver delivery means, including the drawing-off rolls, drawing-off aprons and delivery rolls, all of well-known construction, whereby the sliver S is delivered at the point 8 and the sliver R at the point 9 and 80 is carried from such points into the trumpet T, all of which, as shown in Figs. 1, 2, 3, 8 and 9, is revolute in a well-known manner. In such combs, the mouth of the trumpet T is substantially in line with and midway 85 between the points 8 and 9. Each sliver S and R therefore makes substantially a right-angular turn at the trumpet.

In such combs, the trumpet T is ordinarily 90 revolute in a suitable casing, being driven by a pulley, such as 12, and the sliver 16, where it emerges from the end 15, has a slight twist or false twist which helps to hold it together as it is delivered to the can coiler.

95 F represents the frame which supports trumpet T, having parts 13 and 14 which serve as bearings therefor.

The feeler or faller wires 35 and 36 are pivoted on each side of the frame F and are 100 bent up in such manner that, unless held back by the sliver R or S, gravity will cause them to drop forward. These faller wires are the means for detecting any break in the sliver and starting in operation the mechanism for stopping the comb. There is a faller wire 35 or 36 for each silver ribbon R and S.

As shown, each faller, such as 35, is fixed to a finger, such as 30, which has a nose 31 and a slot 32 through which passes a pin 33 into frame F which serves as a pivot for the finger and faller. It is evident that when the sliver on either side breaks, its corresponding faller wire, such as 35, will swing on its pivot 33 and drop forward, carrying with it finger 30 and nose 31, provided the parts are properly balanced, as shown in Fig. 4. As a very slight difference in weight will cause this action, the faller is very sensitive but does not cause enough friction or drag on the sliver to cause it to break or otherwise interfere with its operation. We may provide a suitable stop, such as 37, to limit the drop of the faller wire.

Such combs are provided with means for stopping and starting them, which it is not necessary to describe, shown as a shipper rod H having a handle 7. To operate such shipper, we provide trigger means, to be described, operative by connecting rod K. As shown, when rod K is pushed up, it operates trigger mechanism which releases means whereby the shipper is operated and the comb is stopped.

For convenience in attachment and adjustment, we show connecting rod K, of telescopic construction, comprising a tube 46 into which slips a rod 45. By means of a set screw 47, which bears on rod 45, its position and the length of K can be adjusted.

At the end of rod K we show a universal joint 44 to which is connected a fork M comprising legs 40 and 41 connected by a bar 42, as shown in Fig. 2.

The part 14 of frame F has grooves, such as 17, in which legs 40 and 41 slide, while the downward movement of fork M is limited by 42 striking the top of 14.

The bottom ends of 40 and 41 are so positioned that each is directly over the top end of a finger, such as 30, pivotal with a faller wire 35 or 36, when such faller wire and finger are not held back by the sliver. When a sliver, such as S, breaks, its faller wire drops forward and its finger moves under the end of a leg 40 or 41 of fork M, as shown by the full lines in Fig. 4.

As the faller and finger are both pivotal on a pin which passes through a slot in the finger, both can be raised, and when the faller is forward, such raising will lift the leg 40 or 41, whichever is above it, and thus fork M and rod K, operating the trigger mechanism to stop the comb.

As a means to so lift each finger, we prefer to attach to or cut in trumpet T a worm 20, and to support in suitable bearings in frame F a shaft 22 which carries a worm gear 21 in engagement with the worm 20, and also carries at each end one or more tappet cams 23 in such position that, when a faller wire drops forward, the nose 31 of

its corresponding finger 30 will drop into the path of a cam 23 and will be lifted thereby as it rotates with trumpet T.

As a means adapted to so move the shipper as to stop the comb, we prefer to provide an actuator L separate from the shipper rod. This actuator comprises a suitable guide tube 49 attached to the frame of the comb by hangers 4 and 5 and the rod 50, which slides inside tube 49. This rod 50 is normally pressed over to the right by a compression spring 6 whereby a dog 2, carried by rod 50, unless prevented, would so engage an arm 3 fixed to the shipper rod H, see Figs. 2 and 6, as to so move the shipper that it will stop the comb.

We provide trigger mechanism to hold such comb stopping means out of action, shown in Figs. 5 and 7 as a trigger 51 pivoted at 52 in a slot 58 in rod 50 and normally held down by spring 54, so that when rod 50 is moved against the spring 6, the nose 53 of trigger 51 will spring down in front of sear 55 pivoted at 56 and connected at 57 by arm 48 to rod K. A stop 59 limits the downward movement of trigger 51.

When 56 and 55 are turned by 48 to the dotted line position shown in Fig. 7, the pressure of spring 6 causes nose 53 to slip over the flat face of 55 and over stop 59, releasing rod 50.

When the sliver breaks and a faller wire drops forward, the mechanism including a finger, such as 30, and fork M engage, and these, being operative by the trumpet guide through the connecting rod, release the trigger and thus the stopping spring 6, whereby the shipper, which is the means to stop the comb, is operated.

90 and 91 indicate the aprons forming part of one of the sliver delivery means, such as D or E, and 92 indicates an apron roll carried in a bearing 93 capable of movement backward when an apron breaks and winds up either on roll 92 or roll 94, or when the sliver breaks and winds up on roll 94. When this happens, bearing 93 moves backward in a well-known manner.

Such aprons run on fluted rolls and wear out very rapidly. When they become weak, they should be removed and replaced but, if neglected, they break and wind up on the rolls. The sliver also breaks and winds up. The breaking and winding up of an apron or sliver causes bad work and frequently the bending and breaking of the adjoining pins.

With our stop motion, we prevent this by providing an apron arm, such as 95, pivoted at 96 to the frame at any fixed point and to bearing 93 at 97, preferably so that a comparatively small movement at that end will mean a much greater movement at the free end, which is bent down at 98 and over at 99 behind one of the faller wires, such as 36, as shown in Fig. 10. When an apron breaks

and winds on a roll, forcing back the bearing, such as 93, arm 95 is so moved as to move forward a faller, such as 36, by direct contact, or moves the adjoining sliver, such as R, forward, whereby, in either case, the comb stopping mechanism is thrown into operation and the comb is stopped.

In Figs. 8 and 9, we show a somewhat simplified construction which may be used 10 with some classes of work. The faller wires 70 and 71 are pivoted as on a rod 72, and each has an extension, such as 73 or 74, on which slides a tube 75 or 76. Tube 75 carries a plate 77, and tube 76 a plate 78, which 15 extend across the trumpet and overlap each other.

When the sliver, such as 10, is unbroken, it holds back wire 70 and extension 73 and thus tube 75 and plate 77, and when the 20 sliver breaks, the wire, such as 71, drops forward, carrying with it plate 78 into such position that, as the pin 79, fixed to trumpet T, revolves, it lifts 78 and 76 as shown in Fig. 8.

25 The connecting rod P has a joint 44 and connects with a slide rod 82 vertically slideable in an extension 81 of frame F. As shown in Fig. 9, a stop 83 allows the bottom end 80 of rod 82 to be held in position just 30 over where plates 78 and 77 will be when their respective faller wires drop forward.

In Figs. 8 and 9, 60 is the shipper rod, supported in bearings 61—61, having a dog 62 between which and a bearing 61 is a 35 spring 63, the tendency of which is to throw the shipper to the left and stop the comb.

The top of rod P is bent over at 64 to form a latch or trigger which, when rod P is down, holds back dog 62 and shipper 60, 40 but when rod P is pushed up, releases both and allows the comb to stop. Fig. 8 shows rod P up, and Fig. 9 shows it down.

As shown in Fig. 4, especially where the mouth of the trumpet revolves, we prefer to 45 use a guard G attached to frame F extending out around the mouth end of the trumpet to prevent the sliver from getting caught between the revolving mouth and its bearing.

On some combs, the sliver-receiving 50 trumpet does not revolve. To adapt such a trumpet for our attachment, we cut it off along the line X, shown in Fig. 4, so as to divide it into the mouth part 18 and the other part 19. The mouth part we fix in 55 the frame F by any suitable means, and the other part 19 we make revolute in the bearings 13 and 14 and attach to it a pulley 12 and cut in it the worm 20 as in the first described construction.

60 In some combs the apron roll bearings, such as 93, are arranged to move radially substantially away from the trumpet instead of at right angles, as shown in Fig. 1.

1. In such a case, as shown in Fig. 11, instead of pivoting the rods such as 95, we

merely attach each to a bearing and bend the ends of each at a suitable angle, as shown at 100 and 101, whereby when the bearing, such as 93, moves away, instead of moving rod 95 pivotally, it pulls it to the 70 dotted line position whereby its adjacent faller wire, 36 or 35, is pushed over to the dotted line position as shown.

With our device, when a break occurs, it is necessary only to throw over the shipper 75 with one hand and feed the sliver into the trumpet with the other until there is sufficient tension to hold back its faller wire, after which no attention need be paid to it until the comb is stopped by another break 80 of the sliver or of the apron.

We claim:

1. In a comb having a movable shipper rod for starting and stopping, a revoluble trumpet guide, means to revolve the trumpet guide while the comb is running, and one or more sets of sliver delivery means, the combination of a faller wire so pivoted as to be held back by the sliver as it passes from a sliver delivery means to the trumpet, 90 a finger carried by said wire, a cam revoluble by the trumpet in such position as to engage and move the finger when the faller wire drops forward, means adapted to so move the shipper as to stop the comb, trigger mechanism to hold such comb stopping means out of action, and a connecting rod between the trigger mechanism and the finger.

2. In a comb having a movable shipper 100 rod for starting and stopping, a revoluble trumpet guide, means to revolve the trumpet guide while the comb is running, and one or more sets of sliver delivery means each including an apron and an apron roll carried in bearings capable of movement backward when the apron breaks, the combination of a faller wire so pivoted as to be held back by the sliver as it passes from a sliver delivery means to the trumpet, a 105 finger carried by said wire, a cam revoluble by the trumpet in such position as to engage and move the finger when the faller wire drops forward, means adapted to so move the shipper as to stop the comb, trigger mechanism to hold such comb stopping means out of action, and a connecting rod between the trigger mechanism and the finger, together with an arm so attached to an apron roll bearing that it causes the 110 faller wire to move forward when such bearing moves backward.

3. In a comb having means for stopping and starting, a trumpet guide revoluble with the comb, and sliver delivery means, the combination of a faller wire so pivoted as to be held back by the sliver as it passes from the sliver delivery means to the trumpet guide, and mechanism engageable when the faller wire drops forward and op- 125 130

erative by the trumpet guide to cause the stopping means to stop the comb.

4. In a comb having means for stopping and starting, a trumpet guide revoluble with the comb, and sliver delivery means, including an apron and an apron roll carried in bearings capable of movement backward when the apron breaks, the combination of a faller wire so pivoted as to be held back by the sliver as it passes from the sliver delivery means to the trumpet guide, and mechanism engageable when the faller wire drops forward and operative by the trumpet guide to cause the stopping means to stop the comb, together with an arm so attached to an apron roll bearing that it causes the faller wire to move forward when such bearing moves backward.
5. In a comb having means for stopping and starting, a sliver receiving guide part of which is revoluble with the comb, and sliver delivery means, the combination of a faller wire so pivoted as to be held back by the sliver as it passes from the sliver delivery means to the sliver receiving guide, and mechanism engageable when the faller

wire drops forward and operative by the revoluble part of the sliver receiving guide to cause the stopping means to stop the comb.

6. In a comb having means for stopping and starting, a sliver receiving guide part of which is revoluble with the comb, and sliver delivery means, including an apron roll carried in bearings capable of movement backward, the combination of a faller wire so pivoted as to be held back by the sliver as it passes from the sliver delivery means to the sliver receiving guide, and mechanism engageable when the faller wire drops forward and operative by the revoluble part of the sliver receiving guide to cause the stopping means to stop the comb, together with an arm so attached to an apron roll bearing that it causes the faller wire to move forward when such bearing moves backward.

In testimony whereof we have affixed our signatures:

CHARLES E. JEWETT.
FRED FITZGERALD.
